Primary Examiner — Darlington Ly(74) *Attorney, Agent, or Firm* — Birch, Stewart, Kolasch & Birch, LLP(57) **CLAIM**

The ornamental design for a display panel for vehicle instrument cluster, as shown and described.

DESCRIPTION

1. Display panel for vehicle instrument cluster

1.1 is a top, front, and right side perspective view of a display panel for vehicle instrument cluster showing our new design;

1.2 is a front elevation view thereof;

1.3 is a rear elevation view thereof;

1.4 is a left side elevation view thereof;

1.5 is a right side elevation view thereof;

1.6 is a top plan view thereof; and

1.7 is a bottom plan view thereof.

The broken lines depict portions of the display panel for vehicle instrument cluster that form no part of the claimed design.

1 Claim, 7 Drawing Sheets(56)
